TOY MOTOR UNIT

John W. Ryan, Bel Air, Calif., assignor to Mattel, Inc., a corporation of California

Filed Apr. 17, 1964, Ser. No. 79,557

Term of patent 14 years

(Cl. D90—1)

FIGURE 1 is a perspective view of a toy motor unit showing my new design, with a control unit for same being shown in broken lines for illustrative purposes only;

I claim:

The new and ornamental design for toy motor unit, substantially as shown and described.
